CLAIM

The ornamental design for a bottle that contains vanilla bean and alcoholic spirits, as shown and described.

DESCRIPTION

FIG. 1 is a perspective view, showing the new design for a bottle that contains vanilla bean and alcoholic spirits;

FIG. 2 is a top view thereof;

FIG. 3 is a side view thereof; and,

FIG. 4 is a bottom view thereof.

The broken lines shown in the drawing disclosure are for illustrative purposes only and form no part of the claimed design.

The shading on the bottle is provided to illustrate contour only; it is not indicative of texture or gloss. The shading within the vanilla bean profile is only provided to illustrate that a vanilla bean is present; the bean shading, and texture and configuration represented by the shading, do not form a part of the claimed design.
